UNITED STATES PATENT OFFICE.

GEORGE POGGENBURG, OF NEW YORK, N. Y.

GAME.

SPECIFICATION forming part of Letters Patent No. 425,249, dated April 8, 1890.

Application filed November 12, 1889. Serial No. 330,070. (No model.)

To all whom it may concern:

Be it known that I, GEORGE POGGENBURG, a citizen of the United States, and a resident of New York, in the county of New York and 5 State of New York, have invented certain new and useful Improvements in Games, of which the following is a specification.

My invention relates to an improvement in games, and more particularly to a game in 10 which a game-board of peculiar construction is made use of, such construction of board being hereinafter fully described, the game itself being one which I fancifully term a game of "Give and take."

15 In order to fully describe my invention, I have illustrated in the accompanying drawings, Figure 1, a top plan view of a board constructed in accordance with my invention, and in Fig. 2 a longitudinal section view taken 20 on the line $x-x$ of Fig. 1.

The board upon which the game is played, and which I have illustrated by the above-mentioned drawings, is preferably constructed of thin wood, it being obvious, however, that the same may be constructed of 25 card-board, papier-maché, sheet metal, or of any other desired material, A being the base-board, having the flange a passing entirely around its outer edge, in order to prevent the 30 marbles or similar articles used in the game from rolling off or falling from the said board A.

I prefer, as is shown in the drawings, to construct one end of the board somewhat larger, both in breadth and thickness, than 35 the opposite end, and provide such enlarged end with pockets, the latter being either hollowed out of the wood or other material of which the base A is constructed, or, in lieu 40 thereof, such enlarged end of the base A may be provided with holes, and have secured thereto pockets made of netting, wood, fabric, or other desired material. The outer pockets are made somewhat smaller than the central 45 pocket B, it being the object to protect the central or larger pocket B by the smaller surrounding ones, the four smaller corner pockets b being designated "give" pockets, and the four inner pockets b' being designated 50 "take" pockets. This board, constructed as above described, may of course be made of any size or dimensions, and, if desired, made in two sections hinged, as shown, in order that it may be folded up and conveniently 55 carried or transported. The top of the board

A may be covered with oil-cloth or other material, but of course, if desired, may be left unprotected and polished.

The game to be played in connection with this board may be described as follows: Each 60 person in the party engaged in the game is supplied with a marble or other similar article, and he in turn, standing at the narrow end of the board—that is, the end farthest from the pocket—attempts to shoot or roll the 65 marble into the central or larger pocket B. If the person should roll the marble into either of the four pockets marked "give," such person pays to the central or larger pocket B such a forfeit as may have been determined upon prior to starting the game. If, however, a person rolls the marble into 70 either of the four pockets marked "take," such person takes from the larger or central pocket one forfeit, or more if such has been 75 so prearranged. A person succeeding in getting the marble into the central pocket B takes the entire contents of the pocket.

I would have it understood that I do not 80 limit my invention to any particular shape or dimensions of the board, nor of the material of which it may be constructed, nor of the number of pockets formed therein, nor should my claim be limited to the use of marbles, as it is obvious that the board may 85 be constructed of such a size as to be capable of being used in connection with billiard-balls or with hollow spheres, and, further, it is obvious that the forfeit may be of any kind or character.

90 What I claim as new, and desire to secure by Letters Patent, is—

The game of "Give and take" hereinbefore described, in connection and to be played with a board constructed with the base A, 95 provided near one end with the larger central forfeit-pocket B, and with the outer smaller corner pockets b , marked or designated "give," and with the inner smaller pockets b' , marked or designated "take," said 100 board to be used in connection with marbles or like articles.

Signed at New York, in the county of New York and State of New York, this 11th day of November, A. D. 1889.

GEORGE POGGENBURG.
